SIZE CONTROL MECHANISM

Robert S. Elberty, Jr., Waynesboro, Pa., assignor
to Landis Tool Company, Waynesboro, Pa.

Application August 12, 1941, Serial No. 406,560

3 Claims. (Cl. 51—165)

This invention relates to size control mechanisms, particularly of the type which do not make use of a member for engaging the machined surface during a machining operation.

This invention is similar to that disclosed in my copending application Serial No. 299,369 filed October 13, 1939, now Patent No. 2,280,692, granted April 21, 1942, and is shown as applied to a machine similar to that disclosed in Patent No. 2,248,172. However, certain parts have been redesigned, others rearranged, and additional functions added, all of which has resulted in more accurate size control. For example, it has been found that more accurate results are obtained if the air nozzle instead of the abutment is mounted on the pivoted member. Provision has been made also for resetting the feed actuated member so that in the event of slight wheel wear the air nozzle will continue to function properly. If the wheel wear is slight, variation in work size will be slight. When the nozzle is released upon removal of a work piece from the caliper there will be only sufficient movement toward the abutment to effect a slight adjustment of same. If a grinding operation is started under such circumstances, the space between the nozzle and abutment is such that the first contact is closed and the feed rate is immediately reduced to finishing speed. By resetting the nozzle for each grinding operation, this difficulty has been overcome. Finally, the adjustment which determines the amount of advance for the abutment has been made more accessible.

Figure 1 is a partial sectional end elevation of the wheel support, feed mechanism, and size control mechanisms.

Figure 2 is an end elevation partly in section and showing a close-up of my size control mechanism.

Figure 3 is a partial plan view of the size control mechanism, grinding wheel support, and work support.

Figure 4 is a section along the line 4—4 of Figure 3.

Figure 5 is a section along the line 5—5 of Figure 3.

In the drawings, numeral 10 indicates the bed of a grinding machine, 11 a wheel support slidably mounted thereon for movement toward and from grinding position, 12 a hydraulic motor for moving said wheel support toward and from grinding position, and 13 a handwheel and associated mechanism for adjusting the position of said wheel support. A grinding wheel 14 is mounted on a spindle 15 which in turn is rotatably supported in a housing 16. A pulley 17 at 55

the opposite end of said spindle is driven thru a belt 18 from a jackshaft 19 and a motor not shown. A work piece 20 is rotatably supported on a work drive spindle 21 by a chuck 22.

5 The size control mechanism consists essentially of two members, an air nozzle 30, and an abutment 40, against which said nozzle is directed. Said abutment consists of an elongated cylindrical member slidably supported in a bushing 42 which is in turn supported in a tube-like guide member 43 forming a part of bed 10. A link 44 attached to abutment 40 is also connected to a shaft 45 which extends toward the front of the machine. By means of this arrangement 15 the operator may adjust or reset abutment 40 manually.

Nozzle 30 is part of a mechanism which consists of a member 31 slidably mounted on slide surface 32 on a frame work 34 which may or 20 may not be a part of the bed 10. A pair of arms 35 extend downwardly from said slide. Between said arms is pivotally supported on pivot points 36, a support member 37 for nozzle 30. Said nozzle is adjustably mounted in a slot 38 in said 25 support member and held in adjusted position by means of a nut 39 on a threaded portion thereof. Adjustment of said nozzle in said slot may be effected by means of adjusting screw 46. The upper portion of support 37 consists of two 30 fingers 50 and 51 which extend thru an opening in slide 31. A dial indicator 54 is mounted on said slide adjacent finger 51 and adapted to be actuated thereby. At the front end of said 35 slide is a hardened surface 52 which forms the anvil of a caliper mechanism. A pair of spaced vertical pins 53 having hardened points for engaging the ground surface of a work piece 20 are inserted in said slide. Finger 50 also having a hardened point for engaging a ground surface, 40 is the movable portion of the caliper.

Attached to nozzle 30 is a connection 55 to a supply of air under pressure (not shown). Said connection has a handle 56 formed thereon so that finger 50 may be withdrawn to release a work piece 20 from the caliper. A spring 57 suitably attached to support 37 and another part of slide 31 urges nozzle 30 toward abutment 40. Movement of support 37 about its pivot may be adjusted by screw 60 in handle 56. Said screw is adapted to engage a beveled surface 58 on the underside of slide 31 and thus to limit the amount of movement of nozzle 30.

Air is supplied to nozzle 30 by any suitable means thru a line 80 in which is inserted a venturi 81 in connection with a manometer tube

82. Mercury in said manometer tube when acted on by fluid under pressure will close a circuit thru electrical contacts 83 and 84. Said circuit includes a solenoid 85 which is connected to actuate a reversing valve 86. Said valve directs fluid under pressure alternately to opposite sides of motor 12.

The inner end of slide 31 has a vertical portion 65 with a lug 66 at the top thereof and an adjusting screw 67 adjustably inserted near the bottom thereof. A lug 68 is located on wheel support 11 in line with said adjusting screw 67. A hook-like member 69 on said support is positioned to engage the lower end of said vertical portion 65 to prevent excess movement of slide 31 to the left.

A belt guard 70 at the pulley end of spindle housing 16 has a projecting hook-like member 71 adapted to engage lug 66 and advance said slide during the feeding movement of the grinding wheel support 11 as described in detail in my co-pending application.

Operation

A master race or one ground to exact size is placed on the caliper. The abutment bar 40 is retracted from nozzle 30 by means of push bar 45. This will assure enough space between said parts that the mercury switch will not function during the set up or trial grinding operation.

The unground or trial work piece is then placed in the chuck and the grinding wheel moved into grinding position. The wheel is fed by hand for the grinding operation until the work has been ground almost to the desired size.

Slide 31 is then pulled toward the front of the machine until members 66 and 71 are firmly in contact.

The air gap between nozzle 30 and abutment 40 is set by pulling bar 45 toward the front of the machine and thus shifting abutment 40 toward nozzle 30 until the second contact is closed in the mercury switch. Closing this contact will cause the wheel to be removed to inoperative position.

The master ring is left on the caliper while screw 60 is turned until it engages the surface 58. The master ring may then be removed. Then, when handle 56 is released nozzle 30 will move toward abutment 40 until screw 60 engages surface 58.

Screw 60 is then backed off until nozzle 30 engages abutment 40. Wheel wear is then determined either by estimate or by observing the difference in indicator readings for successively ground pieces. Screw 60 is then backed off an additional amount equal to the above determined wheel wear. When handle 56 is released with no race on the caliper, this setting of screw 60 will permit nozzle 30 to engage abutment 40 and shift same by the amount of the wheel wear, that is, until screw 60 engages surface 58. This adjustment of abutment 40 is the compensation for wheel wear. If the rate of wheel wear changes, the above procedure must be repeated.

The trial piece which has just been ground is placed in the caliper and another unground race is placed in the chuck. Handle 56 is depressed to increase the air gap between nozzle 30 and abutment 40. Said handle is held in depressed position until the wheel moves into grinding position, and then slowly released. If mercury rises to the finish contact, the setting of screw 67 must be changed so that when engaged by block 68 as the wheel moves from position A

to the extreme front or B position of wheel base 11, slide 31 will be adjusted to increase the space between nozzle 30 and abutment 40. This prevents premature operation of the sizing device especially where wheel wear is not great enough to cause a reset of abutment 40. The reverse movement from position D to position C is the same as the rapid portion of the movement from C to D. However, a feeding movement occurs after the rapid movement and therefore the reverse movement which begins at the point to which the wheel and wheel support have advanced does not return all the way to position C but only a distance equal to the rapid movement toward D and therefore lug 68 will not engage screw 67 on this movement. After reset screw 67 has been set the device is ready to control the grinding operation accurately until another set up becomes necessary due to a change of wheels or size of work.

The trial piece which has been ground a slight amount under-size say .002 inch, is removed from the chuck and placed on the caliper. An unground piece is placed in the chuck and the grinding cycle started.

As the wheel base 11 moves to position B, lug 68 engages screw 67 and shifts slide 31 to increase the space between nozzle 30 and abutment 40. When the wheel spindle is shifted axially to place wheel 14 in position C, projecting member 71 moves into operative relation with lug 66 on slide 31. As wheel 14 moves to position D slide 31 and hence nozzle 30 are moved at the same rate and in the same direction due to the relation between members 66 and 71.

The piece on the caliper which is .002 inch under-size sets the caliper to compensate for this undersize. Since the space between nozzle 30 and abutment 40 was determined first with a piece of exact size, the trial piece being .002 inch undersize will increase the spacing one half this amount or .001 inch. This will allow the base 11 and wheel 14 to move .001 inch further than during the grinding of the piece now on the caliper, plus the amount abutment 40 was shifted to compensate for wheel wear.

From this point on, work pieces of the same size may be ground successively to size within close limits. Any variation from size will correct itself since each piece removed from the chuck is placed on the caliper and determines the setting of the size control mechanism for the next piece.

I claim:

55. 1. In a grinding machine, a grinding wheel support, a grinding wheel rotatably mounted thereon, a work support, mechanism for effecting a relative feeding movement between said supports, a size control mechanism having cooperating elements, one of which is held in a fixed position during a grinding operation, the other of which moves, with said feeding movement, means responsive to the relative movement between said elements for controlling said feeding mechanism, a pivoted member for supporting one of said cooperating elements, a caliper member forming a part of said pivoted member, said pivotally mounted element being operable in the absence of a work piece on said caliper for engaging the other size control element for adjusting same by an amount corresponding to the wear of the grinding wheel during the previous grinding operation, and an adjustable stop on said pivotally mounted member for determining the extent of said adjustment.

2. In a grinding machine, a grinding wheel support, a grinding wheel rotatably mounted thereon, a work support, mechanism for effecting a relative feeding movement between said supports, a size control mechanism having cooperating elements, one of which is held in a fixed position during a grinding operation, the other of which moves with said feeding movement, means responsive to the relative movement between said elements for controlling said feeding mechanism, a pivoted member for supporting one of said cooperating elements, a caliper member forming a part of said pivoted member, said pivotally mounted element being operable in the absence of a work piece on said caliper for engaging the other size control element for adjusting same an amount corresponding to the advance in feed during the preceding operation, a stop on said pivotally mounted member, and means for adjusting same to change the amount of feed for the next operation.

20

3. In a grinding machine, a work support, a wheel support, mechanism for effecting a relative positioning movement between said supports, mechanism for effecting a relative feeding movement between said supports, a size control mechanism comprising cooperating members one of which is mounted on a slide and movable toward the other in response to a feeding movement of said wheel, means responsive to the relative movement between said members for controlling said feed mechanism, means operable to reset one of said cooperating members after each grinding operation to compensate for wheel wear, and additional reset means responsive to a preliminary part of said positioning movement to reset said sliding member in case wheel wear is not sufficient to cause resetting of said other member.
